United States Patent Office

Des. 228,545
Patented Oct. 9, 1973

228,545

KNIFE

Frank G. Beddick, Franklinville, N.Y., assignor to
Queen Cutlery Company, Titusville, Pa.

Filed Feb. 7, 1972, Ser. No. 224,376

Term of patent 14 years

Int. Cl. D8—03
U.S. Cl. D8—99

Fig. 1.

Fig. 2.

Fig. 3.

Fig. 4.

Fig. 5.

Fig. 6.

FIG. 1 is a side elevational view of a knife, showing my new design;

FIG. 2 is a view thereof in end elevation;

FIG. 3 is a top plan view thereof;

FIG. 4 is a view of the opposite side thereof, in elevation;

FIG. 5 is a view of the opposite end thereof, in elevation; and

FIG. 6 is a bottom plan view thereof.

I claim:

The ornamental design for a knife, substantially as shown.
